ZENAS B. LEONARD, OF CLEVELAND, OHIO.

SPRING-CAMBERING MACHINE.

Specification of Letters Patent. Patented Aug. 22, 1916.

1,195,241.

Application filed October 11, 1915. Serial No. 55,317.

To all whom it may concern:

Be it known that I, ZENAS B. LEONARD, a citizen of the United States, residing at Cleveland, in the county of Cuyahoga and State of Ohio, have invented certain new and useful Improvements in Spring-Cambering Machines, of which the following is a specification.

This invention relates to a spring cambering machine, and the primary object of the invention is to provide a die or former adapted to be reciprocated in a horizontal plane in co-acting relations with a pressure-applying member to produce two curved leaf springs in each cycle of movement.

A further object is embodied in the oscillatory die or former which is adapted to be inverted to permit successive cambering operations on a plural number of springs.

Other objects are also embodied in the means for removably securing the cambered springs upon the die or former and in other details of construction, all as hereinafter more fully described.

In the accompanying drawings, Figure 1 is a plan view of my improved cambering machine. Fig. 2 is a longitudinal section vertically through the machine. Fig. 3 is a detail view illustrating the rack and segment for oscillating and reversing the die supporting member. Fig. 4 is an enlarged plan view of the bolt mechanism for locking the die. Fig. 5 is a sectional view of one end of the die member and locking bolt therefor. Fig. 6 is an enlarged cross section of the machine through the pressure-applying roller, showing a spring leaf in cross section upon the die beneath the roller. Figs. 7 and 8 are similar transverse sections of the die member in inverted positions to show the releasing operation of the respective gripping fingers for the dies.

The machine comprises a main frame 2, preferably in the form of a metal tank adapted to contain a large body of oil or other suitable quenching or tempering liquid. Tracks or guides 3 are mounted longitudinally upon the sides of this tank, and a sliding carriage 4 is adapted to be reciprocated in a horizontal plane on said guides by a pair of screws 5 having rotatable bearing in journal boxes 6 on the ends of the tank. Nuts 7 on the carriage 4 engage with the screws, and worm gearing 8 driven by a countershaft 9 and bevel gears 10, 11 and 12 operate the screws by power derived from

electric motor 14. An electric solenoid 15 is adapted to shift the clutch mechanism 16 to produce reversal movements of the screws 5 when the carriage 4 approaches the end of its travel at the opposite ends of the machine, and electrical contacts 17 and 18 and an electric circuit 19 operate the solenoid. Obviously, the reciprocable movement of carriage 4 and control thereof may be produced by any other suitable and practical working device.

Carriage 4 is open at its center and an oscillatory member 20 therein has a transverse shaft or trunnion 21 journaled centrally on the carriage. Sector gears 22 and 23 are fixed upon the opposite ends of shaft 21 and adapted to mesh with short gear racks 24 and 25 fixed upon the tank walls at diagonally opposite points near the ends of the tank. In this way the oscillatory member 20 is oscillated or given one-half of a turn or revolution when the carriage 4 travels to each end of the tank and before it comes to a stop and is reversed in its travel. Each sector gear rides free of the rack last engaged, and the untoothed portion travels over the rack without engaging it upon a return movement of the carriage. The opposite flat faces of the oscillatory member 20 carry curved dies or formers 26 corresponding to the camber or curve to be produced in a blank plate or strip of metal which is fed to the machine in a heated condition from a furnace or furnaces, not shown. However, two inclined guides or chutes 27 are shown as projected from opposite ends of the machine toward the bending or pressure-applying roller to feed the blanks to the machine. This bending roller 28 is carried by a shaft 29 having guiding ends slidably confined within channeled standards 30 fixed upon the machine frame. Shaft 29 is also provided with fixed stud pins 31 adapted to carry removable weights 32 whereby the weight of the roller may be augmented more or less to perform its rolling function to better advantage with different thicknesses of spring plates 33.

To explain further, when the carriage 4 is traveling toward the roller 28 a spring plate 33 is fed down the incline 27 beneath one of the projecting lips 34 at the front end of each die 26. A central annular groove 35 in the periphery of the roller accommodates lip 34 as the die passes beneath the roller, but the roller itself engages and bears down

upon the metal strip 33 as the carriage and die pass beneath the roller, the roller 28 rising and falling and having a rolling movement corresponding in degree to the curvature of the die, obviously shaping the hot blank or plate 33 to exactly the same curvature.

A further forward movement of the carriage and die carrying member brings one 10 sector into meshed relation with one of the racks, whereupon said member is inverted and the curved plate is projected into the oil within the tank, first at one end and then successively or step by step throughout its 15 length until the opposite end is carried beneath the surface of the oil, thus producing a perpendicular quench that will not affect or distort the curvature given to the plate. It is desirable also that the curved plate remain in the oil a minute or more, and for 20 that reason I provide several sets of clamping fingers 36 and 36' at each side of the die member 20 in projecting relations to the cambered surface of each die, where 25 with the blank or plate 33 is securely held upon the die after cambering operations. Each clamping finger is pivotally mounted and spring pressed to throw its beveled end 39 inward over the edge of the blank or 30 plate following the pressing of the blank or plate upon the die as it passes beneath roller 28. In this way when the die member 20 is inverted the curved plate 33 remains suspended in the body of oil during the reverse travel of said die member and while 35 a second plate is being cambered on the upper die.

Release and removal of the curved plate after it has been quenched may be effected 40 at the end of the travel of the carriage subsequent to oscillatory movement of the die member, but as herein shown the quenched plate is released from the fingers and deposited in the bottom of the tank, or upon 45 suitable conveyors therein, after the die member passes beyond the roller 28 and reaches a predetermined position adjacent one of the two sets of inclined brackets 37-37' which are adapted to engage the 50 inner ends of all the fingers of one die at the same time to effect instantaneous release of the curved plate. The two sets of brackets 37-37' are placed in different horizontal planes so that only one set of fingers may 55 be operated during the travel of the die in one direction, and notches 38-38' in the faces of the inner ends of the fingers accommodate the particular bracket 37 or 37' to be avoided during such travel of the die 60 member.

Suitable locking mechanism is employed to hold the die member in a horizontal position after each oscillatory movement thereof. One simple way of accomplishing the 65 desired result is shown in Figs. 4 and 5

consisting of a spring-pressed locking bolt 40 mounted upon the carriage 4 opposite the end of die member 20. This bolt is adapted to seat itself within a socket 41 having a beveled approach 42 upon each half turn of the die member 20. A pivoted lever 43 mounted upon and extending across the carriage 4 is connected to bolt 40, and the ends of this lever are adapted to engage one or the other of two spring pressed pawls 44-45 mounted upon the fixed guide strips 3 at opposite sides of the machine. Pawl 44 is located near the end of the machine and pawl 45 at one side of standard 30, and said pawls are reversely related to unlock bolt 40 by engagement of lever 43 during the travel of carriage 4 in opposite directions immediately preceding or at the instant the sector gears engage the racks to turn the die member 20.

The use of oscillatory or invertible dies traveling in opposite directions alternately beneath a pressure-applying device permits cambering operations to proceed on separate plates under uniform timing operations and at a relatively high speed compared with the present mode of cambering leaf springs where the blanks and finished products are manually delivered and removed from presses. Moreover, in the present invention the plates are rolled to the desired camber by linear contact or over a localized pressure area beginning at one end of the plate or spring and finishing at the opposite end thereof, and in quenching the plate a perpendicular quenching result is obtained by the rotatable movement imparted to the dies. The entire area of the cambered plates is also exposed to the quenching liquid. A rapid cambering operation, uniform standard heats, and perpendicular quenching produce a product of fine quality requiring no peening. Feeding of the blanks may be from one side or both sides of the roller, and such feeding may be accomplished by hand or automatically. In the latter event the automatic mechanism will be associated with the furnace and adapted to co-act in time with the reciprocal movements of the carriage and dies. The dies and rollers might be in multiple and arranged side by side in the same tank, and the tank may be equipped with a conveyor to receive and remove the product after its release from the bottom die, see dotted lines Fig. 6.

It is obvious from the foregoing that other forms of the invention and modifications of details thereof may be adopted without departing from the spirit and scope of the invention as set forth herein and in the following claims, and the claims are to be so construed.

What I claim is:

1. In a spring cambering machine, a hori- 130

zontally reciprocable carriage, a camber die mounted upon said carriage, and a pressure-applying roller in the path of said die adapted to retire relatively thereto to produce a cambered plate by a rolling movement.

2. In a spring cambering machine, a reciprocable carriage having an oscillatory member thereon provided with a plural 10 number of camber dies, a pressure-applying device in the path of said dies, and means to oscillate said member to bring said dies successively in co-acting relations with said pressure-applying device during reciprocable movements of said carriage.

3. In a spring cambering machine, an oscillatory member having a plurality of camber dies mounted thereon, a pressure-applying roller, means to oscillate said member to place said dies separately in position 20 to co-act with said roller, and means to carry said member past said roller.

4. In a spring cambering machine, an oscillatory member having camber dies on opposite sides thereof, a movable carrier for said member, a pressure-applying roller in the path of said dies, means to oscillate said member at intervals, and means beneath said oscillatory member adapted to receive the 30 cambered product.

5. A cambering apparatus, comprising an invertible mounting having camber dies and stock-gripping devices thereon, a pressure-applying roller in co-acting relations with 35 said mounting and dies, means to carry said mounting in opposite directions alternately beneath said roller, and means to invert said mounting and dies after passing said roller.

6. A cambering apparatus, comprising 40 standards, a pressure-applying roller slidably mounted upon said standards, a reciprocable carriage having an oscillatory member thereon, camber dies on opposite sides of said member, means to oscillate said member during reciprocable movements of said carriage, and means to reciprocate said carriage.

7. In a spring leaf cambering machine, a camber die, means to invert said die, a pressure-applying roller above said die, self-acting 50 clamping means to secure the spring leaf upon the die, and means to effect release of the cambered spring leaf from the clamping means subsequent to inverting the die.

55 8. In a machine for cambering metal

plates, a camber die and a traveling carrier therefor, a pressure-applying device in the path of said die, and means to secure the cambered plate successively at different places upon the die following cambering 60 operations.

9. In a machine for cambering spring plates, an invertible camber die and a traveling carrier therefor, a pressure-applying member in the path of said die, gripping 65 devices to secure the plate upon the die subsequent to cambering operations, and means to actuate said devices to release the cambered plate when in an inverted position.

10. In a machine for cambering spring 70 plates, a pressure-applying device, and a set of dies having reciprocal and turning movements relatively to said device to permit a separate cambering operation upon each forward and return movement of the dies.

75 11. In a machine for cambering spring plates, an oscillatory member and a reciprocable carriage therefor, camber dies mounted upon said member, racks and sector gears to oscillate said member, and a pressure-applying member located in the path of said dies intermediate said racks.

12. In a machine for cambering spring plates, an oscillatory member having camber dies thereon and a reciprocable carriage 85 therefor, a pressure-applying device in the path of said dies, means at each side of said device to oscillate said member, a locking bolt for said member, and means operable by the movements of said carriage to unlock 90 said bolt preceding oscillatory movements of said member.

13. In a machine for cambering spring plates, an oscillatory member having camber dies and a set of plate gripping fingers for 95 each die, a pressure-applying device, means to reciprocate said member and dies beneath said device, means to oscillate said member and die subsequent to the travel of said member past said device, and engaging elements for said gripping fingers to effect release of the plates from the dies subsequent to cambering operations thereon.

In testimony whereof I affix my signature in presence of two witnesses.
